EXPLOSION RESISTANT FILTER

Clarence J. Glanzer, Northfield, Ohio, assignor to
 Air-Maze Corporation, Cleveland, Ohio, a corporation of Delaware

Application August 19, 1944, Serial No. 550,157

2 Claims. (Cl. 183—69)

1

This invention relates to improvements in an explosion resistant filter normally adapted to filter a gaseous stream passing therethrough and so constructed that if an explosion occurs in said gaseous stream at or near said filter, the device is not substantially injured by the explosion.

Among the objects of the present invention are the provision of a filter of relatively high efficiency for removing dust or other particles from a gaseous stream and so constructed that it is not torn apart or substantially damaged by a violent explosion in the gaseous stream. The filter also prevents flame travel from the normally downstream side thereof to the normally upstream side. The advantageous features of my invention are clearly described in the accompanying specification and drawings, and the essential features are set forth in the appended claims.

In the drawings,

Fig. 1 is a transverse sectional view through one embodiment of my invention taken along the line 1—1 of Fig. 2, and

Fig. 2 is a top plan view of one corner of the device of Fig. 1 with parts broken away to more clearly show the construction.

For a long time there has been a demand for a filter adapted to remove dust and dirt particles from a stream of air or the like in ducts wherein explosions sometimes occur with such force that an ordinary filter is torn apart, and flame travels along the normally incoming duct. The present invention provides an efficient filtering means which has relatively low resistance to the flow of the air stream, which is able to withstand very violent explosions without any substantial damage, and which prevents flame propagation through the filter.

While my invention may take many forms, I have chosen to illustrate the same as embodied in a rectangular frame 10 of general channel-form section which, for purposes of easy assembly, is made up of a member 11 of L-form having a longer leg 11a forming one of the flat side walls of the frame and having a shorter leg 11b providing a flange around one of the open faces of the filter. At the other face of the filter, an angle member 12 has one leg 12a secured to the leg 11a by means of the metal screws 13. The other leg 12b of this member forms a flange like 11b around one of the faces of the filter. The frame 10 therefore completely incloses the sides of the filter in a duct leaving open front and rear faces 10a and 10b respectively. For purposes of this

2

description, it is assumed that the normal flow of the gaseous stream to be filtered is in the direction of the arrows of Fig. 1 and that when an explosion occurs downstream from the filtering device, an abnormal flow of the gaseous stream will occur in a direction opposed to those arrows.

A second frame 14 is rigidly secured to the inner side walls 11a of the first frame intermediate the front and rear faces of the filter as by means of the welding indicated at 15. This welding is continuous around the perimeter of frame 14 and forms an unbroken seal between frame 14 and frame wall 11a so that flame cannot pass along the inside of wall 11a. It will be noted that the frame 14 is channel-form in section having its web 14a in heat-conducting contact with the walls 11a. In this embodiment of my device, the frame 10 is constructed of sixteen-gauge steel, while the frame 14 is constructed of twenty-four-gauge steel. The frame 14 is filled with explosion-resistant material which, in the present instance, comprises a plurality of layers 16 of brass wire twenty-four meshes to the inch in each direction. This wire screen is provided with closely spaced corrugations about $\frac{3}{32}$ inches in depth, and there are six of these layers shown extending completely across the frame 14 and in planes generally normal to the direction of the gaseous stream flow. It will be noted in Fig. 2, that alternate layers 16a have corrugations extending in one direction while the other layers 16b have the corrugations extending in another direction so as to cross the corrugations of the layers 16a. Thus the corrugations of alternate layers strengthen the layers against bending in different directions, and, because the layers are contiguous, they mutually support each other against the force of an explosion.

The layers 16 being made of brass have high heat conductivity, and the heat of the explosive gases is thus dispersed and conducted toward the frame 14 which in turn conducts the heat to the frame 10. Much of the heat of an explosion is dissipated in this manner.

Filter material is positioned in the frame 10 upstream of the explosion-resistant panel during the normal flow of a gaseous stream through the device. The form of filter material here shown comprises layers 17 and 18 of wire screen having corrugations extending in one direction, say vertically, and alternate layers 19 and 20 of wire screen material having corrugations extending at right angles to the corrugations of 17 and 18, say horizontally. In the example here shown, the layer 17 is of 6x6 mesh having crimps or

corrugations $\frac{5}{8}$ inch deep, the layer 19 is of 6 x 6 mesh having corrugations $\frac{3}{8}$ inch deep, and the layers 18 and 20 are of 8 x 8 mesh having corrugations $\frac{3}{8}$ inch deep. These layers 17 to 20 are for the purpose of filtering out coarser material from the gaseous stream including any lint or material of that character. Downstream from the layer 20 are a plurality of layers 21 (six being shown) of a finer material and preferably of bronze or similar metal. The layers 21 in this embodiment are of 16 x 16 mesh and provided with corrugations $\frac{3}{32}$ inch deep. Preferably also the layers 21 are positioned similarly to the layers 16, that is to say, alternate layers 21a have their corrugations extending in one direction and the other layers 21b have the corrugations crossing the corrugations 21a so as to prevent nesting of the layers and so that alternate layers mutually support each other.

It results from the above-described construction that in the normal use of my device, a stream of air or the like passing through the panel shown in Fig. 1 in the direction of the arrows has substantially all of the dust and dirt particles removed by means of the filtering layers 17 to 21 thus maintaining the explosion resistant panel (consisting of the layers 16) free of dirt and dust. Then, when an explosion occurs, there is a minimum tendency to set the filtering device on fire because the clean screen layers 16 stop the flame propagation, and, because they are clean, it is difficult to start a fire in the filter device. It will be understood by those skilled in this art that the filtering layers 17 to 21 are generally coated with oil or other viscous material so as to catch the dirt particles. Therefore, unless precautions are taken, the oil soaked dust layers on a dirty filter might easily be set on fire.

Preferably, but not necessarily, other layers of material are provided in the frame 10 downstream of the explosion resistant panel in the frame 14. In the present embodiment, this material comprises two layers 22 of 16 x 16 mesh bronze wire having corrugations $\frac{3}{32}$ inch deep and positioned with the corrugations crossing each other as indicated in Fig. 2. The next layer 23 is of 8 x 8 wire mesh with corrugations $\frac{3}{16}$ inch deep, and the last two layers 24 and 25 are of 8 x 8 wire mesh having corrugations $\frac{3}{8}$ inch deep. As indicated in Fig. 2, the layers 23, 24, and 25 have their corrugations crossing to prevent nesting. These layers 22 to 25 serve to obstruct and disperse an explosive gaseous stream ahead of the layer 16 so that the explosion does not strike with full force on the fine layers of the explosion panel. It will be noted also that the layers 22 to 25 are not attached to the frame side walls 11a but are free to give with the explosive force of a stream travelling opposite to the arrows of Fig. 1, such resilient movement of these layers being supported by the frame 14.

The layers 23, 24, and 25 also prevent dirt in the duct downstream from the filter being carried into the layers 16 in case of an explosion downstream.

It will be noted that all of the fine layers 21, 16, and 22 are desirably made of brass or bronze which are metals of high heat conductivity. I have thus provided fourteen layers of this material in the mid-portion of the filter frame, all adapted to disperse and transfer heat from an explosive gaseous stream and to prevent flame propagation in a direction opposite to the arrows of Fig. 1. These fourteen layers also prevent passage of flame from the downstream side of the

filter to the upstream side thereof in case of an explosion downstream.

It should be noted also that I have provided a construction which will operate fairly satisfactorily even if the device is placed in the wrong position in the air duct. The normal position is indicated in Fig. 1, but, if a careless person reverses the faces 10a and 10b, the action of the device will be similar in function although differing somewhat in degree.

What I claim is:

1. An explosion resistant filter comprising a frame adapted to be removably mounted in a duct and having side walls and being open front and rear for the passage of a gaseous stream normally in one direction to filter particles out of the stream and abnormally in the opposite direction upon occurrence of an explosion, filtering means in said frame, a second frame inside said first frame and an uninterrupted integral bond between said first and second frames rigidly attaching them together and preventing by-passing of fluid between them, and a plurality of sheets of foraminous metal extending completely across said second frame in planes generally at right angles to the path of stream flow, each of said sheets having closely spaced parallel corrugations, the corrugations of some of said sheets lying at an angle to the corrugations of other of said sheets, whereby said sheets are stiffened against bending in different directions, and said sheets substantially touching each other whereby they are mutually supported.

2. An explosion resistant filter comprising a frame adapted to be removably mounted in a duct and having side walls and being open front and rear for the passage of a gaseous stream normally in one direction to filter particles out of the stream and abnormally in the opposite direction upon occurrence of an explosion, filtering means in said frame, a second frame inside said first frame and an uninterrupted integral bond between said first and second frames rigidly attaching them together and preventing by-passing of fluid between them, and a plurality of sheets of foraminous metal of the order of wire screen having twenty-four meshes per inch each way, said sheets extending completely across said second frame in planes generally at right angles to the path of stream flow, each of said sheets having closely spaced parallel corrugations of the order of three thirty-seconds inch deep, the corrugations of some of said sheets lying at an angle to the corrugations of other of said sheets, whereby said sheets are stiffened against bending in different directions, and said sheets substantially touching each other whereby they are mutually supported.
